UNITED STATES PATENT OFFICE.

THOMAS A. JENKINS, OF JERSEY CITY, NEW JERSEY.

VENTILATOR.

Application filed August 3, 1921. Serial No. 489,492.

To all whom it may concern:

Be it known that I, THOMAS A. JENKINS, a citizen of the United States, residing at Jersey City, in the county of Hudson and State of New Jersey, have invented certain new and useful Improvements in Ventilators, of which the following is a specification.

This invention relates to improvements in ventilators of vitreous material and more especially to moulded or blown louvered glass plates for window frames and the like.

The primary object of the invention resides in the provision of a single or double glass plate with ventilating openings therein formed with louvers of various, geometrical configurations.

One of the objects of the invention is to produce a window ventilator having two complementary, louvered plates, one adjustable with respect to the other to regulate the draft of air through the louvers and in addition prevent the passing of rain or dust therethrough.

A still further object of the invention is to produce a glass plate ventilator of the type above set forth, wherein the louvers are so arranged that the vision is completely checked, yet permitting the free passage of a predetermined draft of air to a room, car or other enclosure as the case may be.

The invention will be best understood from a consideration of the following detailed description taken in connection with the accompanying drawing forming a part of this specification, with the understanding, however, that the invention is not confined to any strict conformity with the showing in the drawing, but may be changed and modified so long as such changes and modifications mark no material departure from the salient features of the invention as expressed in the subject matter being claimed.

I attain the above objects and others in the accompanying drawing wherein:

Figure 1 is a front view of the ventilator.

Fig. 2 is a sectional view taken on the line A—A of Fig. 1.

Fig. 3 is a front view of a modified form of the invention.

Fig. 4 is a sectional view taken on the line B—B of Fig. 3.

Fig. 5 is a vertical sectional view taken on the line C—C of Fig. 1 showing a single plate.

Fig. 6 is a similar sectional view showing a double set of plates; and

Fig. 7 is a vertical sectional view showing the plates in their adjusted or closed position.

Referring now to the drawings wherein like numerals designate corresponding parts throughout the several views, numeral 1 designates a substantially rectangular frame which may be constructed of metal or wood, and 2 represents a retaining bead for the vitreous plate 3, it being understood that the plates may be moulded or blown.

In the form of the invention shown by Figs. 1 and 2, it will be observed that the louvers 4 extend substantially across the width of the glass plates and from the top and bottom thereof, the said louvers being downwardly curved in the form of a hood so that the draft of air will enter the opening 7 through the passage 8 in the manner shown by the short arrows as clearly set forth by Fig. 5 of the drawing. Numeral 9 designates a complementary glass plate also provided with downwardly curved louvers in the form of hoods, as above described, so that when the respective plates are contiguous disposed with each other the louvers of each plate will produce a substantially semi-circular air passage to permit the draft to enter at 12 and through the opening 13, as suggested by the short arrows of Fig. 6 of the drawing.

Where it is desired to regulate the quantity of air or the draft through the plates, I have provided a thumb screw 6 operable through suitable guides secured to the frame 1 and to the movable plate 3, whereby the passage may be regulated as desired. For instance, in the manner shown by Fig. 7 of the drawing, it will be observed that the flat portions 10 and 11 of the plates are of a length to close the openings in one plate relative to the other and thus entirely exclude the air and prevent the admission of rain.

In the form of the invention shown by Figs. 3 and 4 of the drawing, it will be observed that the louvers 5 are spaced throughout the width and length of the plates and of course, the stationary and movable plates of the frame are adjustable in the same relation as described in connection with Figs. 1 and 2 of the drawings. It will be quite apparent that the configuration or form of the louvers may take various geometrical designs and while I have shown the same in the form of a hood or downwardly curved spherical louver, I do not desire to be limited

ited to this exact form, but contemplate other fanciful and artistic designs to accomplish the same purpose.

Between the respective plates as indicated at 14, I also propose to introduce a dust filtering fabric to exclude foreign matter from entering an enclosure, the same being particularly adapted for use on railroad sleeping cars where the adjustable louvers perform the double function of regulating the draft or quantity of air and completely checks the vision thus dispensing with the necessity of using shades.

The preferred embodiment of the invention is disclosed in the drawings and set forth in the specification, but it will be understood that any modifications within the scope of the claimed invention may be made in the construction without departing from the principle of the invention or sacrificing any of its advantages.

What I claim is:

1. A ventilator element for building constructions and the like comprising two opposed complemental sheets of vitreous material having equally spaced openings, each of said sheets having its outer face provided with integral laterally projecting and depending curved louvers opposing said openings, each of said louvers having its top and sides closed, said louvers extending trans-

versely of the sheets and providing means for directing air through the openings, means connected with the outer face of one of said sheets for shifting it relatively to the other, the portions of said sheets between the louvers being of a width to close the openings of the sheets when one sheet is shifted relatively to the other.

2. A ventilator element for building constructions and the like comprising two opposed complemental sheets of vitreous material having equally spaced openings, each of said sheets having its outer face provided with integral laterally projecting and depending curved louvers opposing said openings, each of said louvers having its top and sides closed, said louvers extending transversely of the sheets and providing means for directing air through the openings, means connected with the outer face of one of said sheets for shifting it relatively to the other, the portions of said sheets between the louvers being of a width to close the openings of the sheets when one sheet is shifted relatively to the other, and a stationary flat foraminous body interposed between said complemental sheets.

In testimony whereof, I affix my signature hereto.

THOMAS A. JENKINS.
